DESIGN FOR A TRANSPARENT DISPLAY LETTER OPENER

Robert E. Gordenier, St. Paul, Minn., assignor to
Brown & Bigelow, St. Paul, Minn., a corpora-
tion of Minnesota

Application November 14, 1947, Serial No. 142,537

Term of patent 14 years

(Cl. D74—1)

To all whom it may concern:

Be it known that I, Robert E. Gordenier, a citizen of the United States, residing in St. Paul, county of Ramsey, and State of Minnesota, have invented a new, original, and ornamental Design for a Transparent Display Letter Opener, for which the following is a specification, reference being had to the accompanying drawings, forming part thereof.

Figure 1 is a side elevational view of a transparent display letter opener, showing my new design having a portion thereof broken away;

Figure 2 is an edge elevational view thereof;

Figure 3 is an end view from the cutting end; and

Figure 4 is an end view from the handle end.

I claim

The ornamental design for a transparent dis-
play letter opener, as shown.

ROBERT E. GORDENIER.
